 3 Claims. (Cl. 260—653.3)

This is a continuation-in-part of application Serial No. 178,970, filed March 12, 1962, now U.S. Pat. No. 3,152,051.

This invention relates to improved methods for pyrolyzing fluoroform to produce tetrafluoroethylene and/or hexafluoropropene.

In the pyrolysis of fluoroform to produce the perfluorinated olefins tetrafluoroethylene and/or hexafluoropropene as disclosed in U.S. Patent No. 3,009,966 of Murray Hauptchein and Arnold Fainberg, one of the major by-products in the pyrolysis is hexafluoroethane C_2F_6 .

While the hexafluoroethane is a relatively minor by-product under conditions providing low fluoroform conversions, it is produced in increasingly larger quantities as the pyrolysis is carried out at increasingly higher fluoroform conversions, and in view of the relatively high cost of the fluoroform starting material, it is highly desirable to reduce the formation of this by-product substantially to zero. While it is possible to virtually eliminate the formation of C_2F_6 by operating the pyrolysis at very low fluoroform conversion rates operation at very low conversions is not desirable since the size of the pyrolysis reactor and associated distillation equipment increases as the rate of fluoroform conversion decreases.

In accordance with the present invention it has now been found that the net production of hexafluoroethane can be reduced to zero by separating the hexafluoroethane from the pyrolylate and recycling the separated hexafluoroethane to the pyrolysis zone together with fluoroform feed-stock until the concentration of hexafluoroethane in the feed to the pyrolysis zone becomes equal to the concentration of hexafluoroethane in the product gases. Provided that the total one pass conversion of fluoroform to products is maintained below about 65% it has been found that upon prolonged recycle of the C_2F_6 a condition will be obtained in which the concentration by weight of the hexafluoroethane in the product from the pyrolysis zone is equal to the concentration by weight of hexafluoroethane in the feed to the pyrolysis, thus resulting in a net formation of C_2F_6 of zero. In order to achieve this result it has been found necessary to maintain the total one pass conversion of fluoroform below about 65%, since above that conversion rate the net formation of C_2F_6 cannot be suppressed by recycle of the C_2F_6 .

It is quite surprising that the net formation of hexafluoroethane in the pyrolysis of fluoroform can be suppressed in the manner described above, since it appears that the mechanism for the formation of C_2F_6 involves the production of elemental carbon, a solid, which tends to deposit out on the walls of the reactor. Although the invention is not limited to any particular explanation for the reaction mechanism, it is believed that C_2F_6 forms according to the following equation:

The observed fact of the suppression of C_2F_6 by its recycle would appear to require an equilibrium between the C_2F_6 in the reactor and carbon deposited on the reactor walls, which is quite unexpected.

It is quite surprising that the recycle of the C_2F_6 does not result in its breakdown to CF_4 or other by-products. As will be seen, the C_2F_6 recycle does not result in any

2

corresponding increase in any of the normal by-products, or the formation of new by-products, even though the reaction is conducted under vigorous conditions of high temperature.

Finally, it is also surprising that the complete suppression of the C_2F_6 is achieved at relatively low concentrations of C_2F_6 in the product and feed gases. Even at relatively high conversions, up to about 65%, the complete suppression of C_2F_6 occurs at a concentration of C_2F_6 in the product and feed gases of not more than about 5%. The concentration of C_2F_6 at low fluoroform conversions necessary to provide complete suppression of net C_2F_6 production is considerably lower than 5%.

Reference is now made to the sole figure of the drawing which shows in diagrammatic form a preferred embodiment of the invention.

Referring to the figure, the reference numeral 1 refers to the line for introducing fresh fluoroform feed into the system. Into line 1 there is also introduced recycle streams 2 and 3 separated from the pyrolysis products which will be described in detail subsequently. The mixture of fresh fluoroform feed and recycled material from lines 2 and 3 pass through valve 4 into a preheater 5 which may be gas fired as shown, then through line 6 to the pyrolysis reactor indicated generally by 7. The pyrolysis reactor comprises a tube or series of tubes 8 which may be heated by any convenient means such as by electrical resistance heater elements 9. The entire pyrolysis furnace is insulated by suitable thermal insulating material 10. The pyrolysis reactor 7 is maintained at pyrolysis temperatures (as described more in detail in U.S. Patent No. 3,009,966) ranging preferably from about 850 to 1300° C. and usually most desirably from about 900° to 1200° C. and at a contact time and pressure adjusted, depending upon the temperature used, to produce the desired rate of conversion of fluoroform to products. The raw pyrolylate from the reactor is conducted by line 11 to a cooler 12 where the pyrolylate is cooled e.g. approximately to room temperature and is then conducted by line 13 to a vacuum compressor 14 which serves to draw a vacuum on the reactor and at the same time serves to compress the pyrolylate to pressures of about 5 to 75 lbs./in.² gage. The compressed pyrolylate is then fed by line 15 to a condenser 16 provided with a cooling coil 17. In the condenser 16, the compressed pyrolylate is cooled to a temperature of about -20° C. to +10° C. which is below the dew point of the hydrogen fluoride product from the reaction but above the dew point of the organic portion of the pyrolylate. As a result, the bulk of the hydrogen fluoride condenses from the mixture and is withdrawn from the bottom of the condenser 16 by line 18 while the organic portion of the pyrolylate passes by line 19 to a compressor 20. The liquid condensate which is comprised almost entirely of hydrogen fluoride is introduced into column 21 where any organic portion is distilled overhead and is removed by line 22 and fed into line 19. The bottoms from column 21 are removed by line 23 and these bottoms comprising substantially pure hydrogen fluoride may be recovered for any desired use.

The organic portion of the pyrolylate leaving compressor 20 is compressed to about 125 to 400 lbs./in.² and is fed by line 24 into extractive distillation column 25. In extractive distillation column 25 the desired products tetrafluoroethylene and hexafluoropropene are separated from unreacted fluoroform and to a large extent from the hexafluoroethane obtained in the pyrolylate.

Where tetrafluoroethylene is a desired product, it has been found necessary to employ an extractive distillation procedure because of the formation of a fluoroform tetrafluoroethylene azeotrope containing about 20% tetra-

fluoroethylene at 0° C. The operation of the extractive distillation procedure, which does not form per se a part of this invention, is described in detail in the co-pending application Serial No. 178,970, filed March 12, 1962, of Arnold H. Fainberg, David S. Fetterman and Murray Hauptschein now United States Patent No. 3,152,051.

The extractive distillation column 25 comprises three main sections, namely section A, section B and section C indicated by the cross-hatching. As can be seen, the organic portion of the raw pyrolysate containing unreacted fluoroform, tetrafluoroethylene, perfluoropropylene, hexafluoroethane and minor amounts of other constituents such as C₄ olefins and C₂HF₅ is introduced between sections B and C. The extractant is introduced between sections A and B by line 26. The extractant is preferably hexafluoropropylene and the operation of the column will be described with reference to that extractant. The short section A of the column above the point of introduction of the extractant prevents the hexafluoropropene extractant from passing out of the column as overhead. In section B the descending hexafluoropropene extractant in effect strips away C₂F₄ from the CHF₃ such that the descending liquid becomes progressively richer in C₂F₄ and the ascending vapors richer in the CHF₃. Unexpectedly, the hexafluoroethane content of the pyrolysate is also separated from the C₂F₄ in section B, rising up the column with the fluoroform rather than descending with the C₃F₆—C₂F₄ mixture. Vapor liquid equilibria measurements for the quaternary system

show that the relative volatility of C₂F₆ with respect to C₂F₄ is substantially in excess of unity, ranging e.g. from 1.2 to 1.3 at temperatures of +5 to -5° respectively for the relatively low concentrations of C₂F₆ that are normally encountered in section B of the column (usually from 0.1 to 10 mol percent of the quaternary mixture). This permits separation of some or virtually all of the C₂F₆ from the C₂F₄ in the extractive distillation column, the C₂F₆ going overhead with the fluoroform.

In section C, the descending liquid mixture is progressively enriched in C₂F₄ and depleted in CHF₃ and C₂F₆. The hexafluoropropene content of the feed stream 46 of course travels down the column with the circulating stream of C₃F₆ extractant. The higher boiling C₄F₈ and C₄F₆ compounds comprising a minor fraction of the pyrolysate also travel down the column.

The extractive distillation column 25 is provided with the usual reboiler coil 29 at the bottom of the column and with the usual condenser 30 at the top. The overhead from column 25 is taken off by line 28 while the bottoms, consisting principally of hexafluoropropene and tetrafluoroethylene, flow by line 27 through valve 31 to a second distillation column where the tetrafluoroethylene and other volatile products are separated from hexafluoropropene and other higher boiling components. The hexafluoropropene and other high boiling components leave the bottom of column 32 by line 33 and are conducted to a pump 34 and are then conducted by line 35 to lines 36 and 37 where the stream is divided into two portions.

The bulk of the stream from line 35 flows through line 36 through a heat exchanger 38 where the temperature is adjusted and then through line 26 to the extractive distillation column 25. A minor proportion of the stream conducted by line 37 to column 39 where the perfluoropropene is distilled away from higher boiling materials such as C₄ olefins and the like, the perfluoropropene being recovered as product from the top of the column by line 40. If desired, the higher boiling materials such as C₄ olefins may be recycled by line 41, valve 42 and line 2 and introduced with fresh fluoroform feed into the reactor. Any minor amounts of even higher boiling ma-

terials are removed from the bottom of column 39 by line 43 controlled by valve 44.

As stated previously, the bulk of the fluoroform and in many cases the bulk of the C₂F₆ contained in the raw pyrolysate is separated from the other products as overhead from column 25. A portion of the column overhead is refluxed back into the column by line 45 and valve 46 while another portion is recycled to the pyrolysis reactor by line 47, valve 48, and line 3.

In a typical operation, most of the fluoroform and hexafluoroethane in the pyrolysis product is recovered as column overhead from extractive distillation column 25 and thus, the main source of fluoroform and C₂F₆ recycle to the pyrolysis reactor in the preferred embodiment shown will be the overhead from the extractive distillation column 25.

In the practical operation of the extractive distillation column 25 however, there may be some minor amounts of fluoroform and C₂F₆ which are contained in the bottom of column 25 and these will be introduced accordingly into the second distillation column 32, where the tetrafluoroethylene and other lower boiling products are separated from hexafluoropropene and other higher boiling products. Accordingly, the overhead from column 32 will often contain in addition to the tetrafluoroethylene, small amounts of hexafluoroethane and fluoroform. This mixture is withdrawn from the top of column 32 by line 49 and introduced into a third distillation column 49a where the hexafluoroethane and fluoroform are separated from the tetrafluoroethylene, the bulk of the tetrafluoroethylene being recovered from the bottom of the column by line 50, while the fluoroform and hexafluoroethane are recovered from the top of the column through line 51. This overhead portion is recycled to the pyrolysis reactor by lines 51 and 52 and introduced into line 3 where it joins the bulk of the C₂F₆ and CF₃H recovered as overhead from the extractive distillation column 25 and is introduced into the pyrolysis reactor together with fresh fluoroform feed from line 1.

As can be seen from the foregoing description of the embodiment shown in the drawing, essentially all of the hexafluoroethane produced in the raw pyrolysate is recovered and recycled to the pyrolysis reactor. The particular techniques used in separating C₂F₆ from the pyrolysis products does not form per se part of the present invention, and it is to be understood that the C₂F₆ may be separated by methods other than by the particular ones shown.

As previously pointed out, it is essential in the present invention to operate the pyrolysis reactor under conditions providing not more than about a 65% one pass conversion of fluoroform products, i.e. to say not more than about 65% of the fluoroform in the mixture entering the reactor through line 6 should be converted into other products during passage through the pyrolysis reactor. The factors of effecting conversion of the fluoroform are principally temperature and contact time. Higher temperatures and higher contact times strongly favor higher one pass conversions of fluoroform. As stated previously, the pyrolysis temperature will be preferably from about 850° C. to about 1300° C. and preferably 900° to 1200° C. while contact times are preferably in the range from about one second to about .001 second, with the shorter contact times being used at higher temperatures. Reaction pressures preferably of one atmosphere or less are used. Somewhat reduced pressures varying from about 100 to 600 mm. Hg absolute are preferred because they appear to favor a more desirable product distribution giving higher total yields of tetrafluoroethylene and/or hexafluoropropene. As discussed in more detail in U.S. Patent 3,009,966 these reaction variables may be readily adjusted to obtain any desired rate of conversion of the fluoroform to products.

As stated previously, the rate of production of hexafluoroethane tends to increase with increasing fluoroform

conversions. This is shown by the following examples in which no recycle of hexafluoroethane to the pyrolysis zone is employed.

Examples 1 to 6

In these examples fluoroform is fed through a platinum lined Inconel reactor tube maintained at a pressure of approximately 100 mm. Hg absolute by a vacuum pump. The reactor tube is heated over a length of about 20 inches to a temperature of 1250° C. as measured by a thermocouple at the center of the tube. The feed rate of fluoroform to the reactor was varied between 0.5 to 1.5 pounds per hour. Over this range of fluoroform feed rates, the conversion of fluoroform to total product varied between about 40% and 85%.

The product gases in these examples were analyzed by passing samples through a bed of sodium fluoride maintained at 80 to 100° C. to obtain quantitative removal of hydrogen fluoride and were then analyzed by gas liquid partition chromatography to obtain the mole percent composition of the product from which was calculated the mole percent conversion of fluoroform and the percent conversion of fluoroform to organic products. The yield of hexafluoropropene plus tetrafluoroethylene was also determined by calculation from this data. The results of Examples 1 to 6 are shown in the following Table I.

TABLE I

Example	Total percent conversion of CHF_3	Percent CHF_3 Converted to—			Other Products	Percent Yield of $\text{CF}_2=\text{CF}_2 + \text{CF}_3\text{CF}=\text{CF}_2$
		$\text{CF}_2=\text{CF}_2$	$\text{CF}_3=\text{CF}=\text{CF}_2$	C_2F_6		
1-----	40.6	35.1	4.5	1.0	-----	97.5
2-----	46.8	38.3	6.8	1.6	0.1	96.4
3-----	55.8	47.3	6.6	1.8	0.14	96.4
4-----	60.8	48.7	9.65	2.3	0.31	96.0
5-----	73.3	60.0	10.3	2.8	0.35	95.5
6-----	85.9	67.5	9.3	8.9	0.35	89.5

As can be seen from Table I, significant amounts of hexafluoroethane are produced at conversions of 40% with the conversion to C_2F_6 increasing as the conversion increases. As the total fluoroform conversion increases above about 60%, the conversion to hexafluoroethane increases markedly.

Examples 7 to 9

The following examples illustrate the effect of recycling C_2F_6 to the reactor at a total one pass fluoroform conversion of about 65%. The same pyrolysis reactor was employed as in the previous examples with a preactor temperature of about 1250° C. and a pressure of about 100 mm. Hg absolute. The rate of feed to the reactor was maintained at a constant rate of 0.75 lb. per hour in these examples. To evaluate the net formation of C_2F_6 it was necessary to calculate a material balance across the reactor for each set of feed and product analyses. For this purpose all analyses were converted to carbon percent, i.e. the percent of the total carbon in the total product contributed by each component. This was done by multiplying the mole percent of each component by the number of carbon atoms in that component and then expressing the thus weighted mole percents as carbon percent by dividing the weighted mole percent of each component by the weighted mole percent of total products. Using this material balance method, the actual weights of C_2F_6 entering and leaving the reactor per 100 pounds of total feed were calculated. In Example 7, no C_2F_6 was introduced into the feed to the reactor; in Example 8, 2.5 weight percent of C_2F_6 was added while in Example 9, 3.8 weight percent was added. The results are shown in Table II.

TABLE II

Example	C ₂ F ₆ in Feed		Lbs. of C ₂ F ₆ produced per 100 lbs. of product (including HF)	Net formation of C ₂ F ₆ , lbs. of C ₂ F ₆ per 100 lbs. of product
	Mole Percent	Wt. Percent		
7-----	0	-----	2.5	+2.5
8-----	1.3	2.5	3.0	+0.5
9-----	1.9	3.8	3.8	0.0

As can be seen from Table II, when no C_2F_6 was recycled the product contains 2.5 weight percent of C_2F_6 representing a yield loss of 2.5% when tetrafluoroethylene and/or hexafluoropropene are the desired products. When the feed contains 2.5% C_2F_6 , the C_2F_6 in the product increases to 3.0 weight percent but the net formation of C_2F_6 drops to +0.5 weight percent. After prolonged recycle, the percent of C_2F_6 in the product increases to 3.8% and when this C_2F_6 is recycled both feed and product contains 3.8% with a net formation of C_2F_6 of zero percent.

Attempts to suppress the net formation of C_2F_6 at total fluoroform conversions of 70% and 80% respectively by recycling C_2F_6 were unsuccessful. Although some suppression occurred, the net formation could not be reduced to zero.

Example 10

A four hour run was made using a platinum lined reactor tube, with an inside diameter of $\frac{3}{8}$ " heated over 20 inches of its length to a temperature of 1230° C. and maintained at a reaction pressure of 150 mm. Hg with the rate of flow adjusted to give a one pass fluoroform conversion of 60%. During the run the reactor feed contained about 3.3% by weight of C_2F_6 the remainder being fluoroform. A total of 1254 grams of fluoroform and 43 grams of C_2F_6 was fed to the reactor during the run (a total feed of 1297 grams). The results of this run were as shown in Table III.

TABLE III

Compound	Weight of product grams	Percent CHF_3 converted to organic product	Percent yield
CHF_3	503	51.4	82.2
$\text{CF}_2=\text{CF}_2$	414	8.39	17.2
$\text{CF}_3\text{CF}=\text{CF}_2$	86	0	0.0
C_2F_6	42	.02	0.03
C_2HF_5	0.2	.06	0.2
C_4F_8	0.9	.03	0.05
Cyclic C_4F_8	0.3	.10	0.3
Perfluoroisobutylene	1.3	-----	-----
HF	223	-----	-----
Totals	1,271	-----	100.0

As can be seen from Table III, the recycle of C_2F_6 resulted in the complete suppression of the net formation of this by-product at a C_2F_6 concentration in the feed and product streams of 3.3% by weight. The material balance across the reactor confirmed this result within experimental error. It is also to be noted that the recycle of

the C_2F_6 in this manner resulted in no increase in the formation of other by-products. In particular no formation of CF_4 was noted. Also there was no net formation of carbon as shown by no carbon deposition in the pyrolysis tube during the run.

Example 11

In another prolonged run at pyrolysis temperatures of about $900^\circ C.$, giving one pass fluoroform conversions of 30%, recycle of C_2F_6 suppressed the net formation of this compound at a concentration of C_2F_6 in the feed and product gases of only about 0.2% by weight.

While the method of the invention will be useful in suppressing net C_2F_6 formation at any rate of fluoroform conversion below about 65% it will be found most useful when the pyrolysis is operated to give fluoroform conversion of from about 20 to 60%.

We claim:

1. In the production of olefins selected from the class consisting of tetrafluoroethylene and perfluoropropene by the pyrolysis of fluoroform at temperatures of from 850 to $1300^\circ C.$ and at contact times of from 0.001 to 1 second, under conditions producing C_2F_6 as a by-product of the pyrolysis reaction, the improvement which comprises separating C_2F_6 from the desired products of the pyrolysis and recycling the separated C_2F_6 to the pyrolysis zone

together with fluoroform feed stock until the concentration of C_2F_6 in the organic product from said pyrolysis zone becomes equal to a value, not more than about 5% by weight of the feed to said pyrolysis, which is substantially the same as the concentration of C_2F_6 in the feed to said pyrolysis zone, while maintaining the total one pass conversion of the fluoroform to other products in the range of from about 20% to about 65%, thereby substantially eliminating the net production of C_2F_6 in said pyrolysis.

5 2. A method in accordance with claim 1 in which the pressure in said pyrolysis zone is maintained at from about 100 to 600 mm. Hg absolute.

10 3. A method in accordance with claim 1 in which the total one pass conversion of fluoroform to other products is maintained in the range of from 20% to 60%.
